Primary Examiner — Philip S Hyder*Assistant Examiner* — Roselynne Cody(74) *Attorney, Agent, or Firm* — Miracle Law LLC; Bryce D. Miracle(57) **CLAIM**

The ornamental design for a tool for snapping and then extracting loop panel ties from concrete, as shown and described.

DESCRIPTION

FIG. 1 is a perspective first view of a tool for snapping and then extracting loop panel ties from concrete, as seen from the rear, right, and bottom end, showing my new design;
 FIG. 2 is a perspective second view of the tool for snapping and then extracting loop panel ties from concrete, as seen from the front, right top end;
 FIG. 3 is a front elevational view thereof;
 FIG. 4 is a right side elevational view thereof;
 FIG. 5 is a rear elevational view thereof;
 FIG. 6 is a left side elevational view thereof;
 FIG. 7 is a bottom plan view thereof; and,
 FIG. 8 is a top plan view thereof.
